31 Claims. (Cl. 167—88)

The present invention relates to the dyeing of human hair, and more particularly to the use of oxidation hair dyestuffs for the dyeing of human hair whereby improved dyeing effects are achieved.

It is known to add reducing substances to hair dyestuff compositions based on the use of oxidation dyestuffs in order to prevent a premature oxidation by the atmospheric oxygen. For this purpose there has been used in hair dyeing compositions hematoxylin (German Patent No. 541,404), inorganic sulfites (Erdmann, Zeitschr. f. angewandte Chemie 1906, volume I, 1053), mercaptans (German Patent No. 839,991) and sodium dithionite (French Patent No. 1,052,622).

Since hematoxylin is practically inactive and sodium dithionite, because of its instability and undesired side reactions, practically unusable, the sulfites and the mercaptans, particularly thioglycolic acid have found practical application in hair dyestuff compositions which are mixed with oxidation agents shortly before use. By preventing the premature oxidation what is achieved is that in the first place the hair dyestuff does not lose its dyeing capacity prematurely, and that on the other hand prior to the mixing with the oxidation agent a light colored, appealing appearance is obtained which remains light colored for a relatively longer time after the application of the oxidation agent. This is important since if the dyestuff mass becomes dark too quickly on the hair the control to the desired time is necessary to achieve the desired degree of dyeing is made more difficult.

With those hair dyestuffs which because of their particular chemical structure can be used as oxidation dyestuffs without the simultaneous use of an oxidation agent, i.e. used alone, because the same are oxidized by atmospheric oxygen in a short time, for example oxidation dyestuffs based on 2,4-diaminophenol (British Patent No. 802,554) the above mentioned reducing agents cannot satisfactorily be used because while the same prevent premature oxidation they simultaneously interfere with the necessary oxidation by means of atmospheric oxygen during the coloring process, and consequently during the normal treatment time only a relatively poor depth of color is obtained, which is quite unsatisfactory. As a result, such oxidation hair dyestuffs in general are used without any reducing agent and can only be used under conditions of considerable care, for example preparation and draining off under nitrogen atmosphere.

It is accordingly a primary object of the present invention to provide hair dyestuff compositions containing oxidation hair dyestuffs either of the type that can be used both with and without an oxidation agent (i.e. including also such oxidation hair dyestuffs which can be oxidized in a relatively short time solely by atmospheric oxygen) and which contain a reducing agent of a special type which gives particularly good results for all types of oxidation hair dyestuffs.

It is another object of the present invention to provide a reducing agent for hair dyestuff compositions which not only prevents premature oxidation from atmospheric oxygen but which also improves the depth of dyeing as compared to hair dyestuff compositions without the reducing agent of the present invention.

2

It is another object of the present invention to provide hair dyestuff compositions which do not require a special oxidation agent but which can be used to achieve the dyeing effect by means of atmospheric oxygen alone and which nevertheless can be applied under ordinary conditions.

It is still another object of the present invention to provide a method of dyeing human hair using the compositions of the invention.

10 Other objects and advantages of the present invention will be apparent from a further reading of the specification and of the appended claims.

With the above and other objects in view, the present invention mainly comprises a composition for dyeing human hair, comprising an oxidation hair dyestuff which is adapted upon oxidation to dye human hair, and a compound selected from the group consisting of ascorbic acid and salts thereof.

The composition may contain an oxidizing agent in 20 addition, by being mixed with an oxidizing agent shortly prior to application to the hair, particularly in the case of the use of oxidation dyestuffs which require an oxidation agent in addition to atmospheric oxygen in order to achieve the dyeing effect in a satisfactory period of 25 time, or the composition, where using an oxidation dyestuff which can be rapidly dyed by means of atmospheric oxygen, may be free of an extra oxidation agent. In either case, as will be proved below, superior dyeing effects are achieved by the use of ascorbic acid or a salt thereof in 30 accordance with the present invention.

It should be noted that the activity of the ascorbic acid according to the present invention is the same with both optical isomers thereof, namely with "Vitamin C," the known L-form, and also with "iso-ascorbic acid," the known D-form. Consequently in all of the discussion in this application whenever the term "ascorbic acid" is used, this refers to both optical isomers, or either one.

In addition to being applicable to the use of either isomeric form of ascorbic acid, the present invention is applicable to the use of all inorganic or organic amine salts of ascorbic acid, particularly those salts the cations of which are used to give an alkaline pH to the composition, for example sodium, potassium, ammonium, and organic amine salts such as monoethanolamine, diethanolamine, triethanolamine, isopropanolamine, and the like.

The present invention is applicable to the use of all common oxidation hair dyestuffs that can be used for the dyeing of human hair, for example those indicated in the Colour Index, 2nd edition, 1956, volume 3, pages 50 3593-3601.

Among the most suitable oxidation hair dyestuffs for use according to the present invention are:

o-phenylenediamine,
55 p-phenylenediamine,
4-nitro-o-phenylenediamine,
4-nitro-o-phenylenediamine-dihydrochloride,
m-phenylenediamine,
4-chloro-m-phenylenediamine,
60 4-nitro-m-phenylenediamine,
toluene-2,4-diamine,
salts of toluene-2,4-diamine,
toluene-2,5-diamine,
5-nitro-toluene-2,4-diamine,
toluene-2,5-diamine-sulfate,
2-chlorotoluene-3,5-diamine,
4-methoxy-m-phenylenediamine,
4-methoxy-m-phenylenediamine-sulfate,
5-methoxy-p-phenylenediamine,
70 4-ethoxy-m-phenylenediamine,
4-ethoxy-m-phenylenediamine-sulfate,
p-phenylenediamine-dihydrochloride,

2-chloro-p-phenylenediamine,
2-chloro-p-phenylenediamine-sulfate,
2-nitro-p-phenylenediamine,
3-(p-aminoanilino)-1,2-propanediol,
N-phenyl-p-phenylenediamine,
N-phenyl-p-phenylenediamine-hydrochloride,
4,4'-diaminodiphenylamine,
4,4'-diaminodiphenylamine-dihydrochloride,
resorcinol,
4-chlororesorcinol,
pyrogallol,
p-aminophenol,
2-amino-4-nitrophenol,
picramic acid,
m-aminophenol,
p-aminophenol-hydrochloride,
1-naphthol,
1,5-naphthalenediol.

It is particularly interesting to note that the ascorbic acid and salts thereof which are used as reducing agents according to the present invention in addition to giving the normal reducing agent effect of preventing premature oxidation of the hair dyestuffs, quite surprisingly, as will be explained below also increase the depth of shade resulting from the use of the hair dyestuff. Thus, with greater amounts of the ascorbic acid or salts thereof the depth of shade is increased and darker shades are obtained.

The amount of the ascorbic acid or salt thereof for the purposes of the present invention may be as little as 0.5% by weight of the composition including the carrier, the oxidation dyestuff and the ascorbic acid, and the maximum amount of the ascorbic acid or salt thereof is to an extent mainly limited by the expense. In general amounts of greater than 10% by weight are not necessary and in order to prevent undue expense should not be used. The most preferred amount of ascorbic acid or salt thereof is about 0.5-3% by weight.

The oxidation dyestuff may be used in any amount ordinarily used for the dyeing of hair, the amount depending of course upon the dyestuff and upon the depth of shade desired. In general amounts of about 0.1-8% by weight are used.

As indicated above the use of ascorbic acid and its salts as reducing agent according to the present invention is equally applicable to oxidation dyestuff compositions in which the oxidation occurs solely by the atmospheric oxygen and to oxidation dyestuff compositions which utilize an oxidizing agent such as hydrogen peroxide, urea peroxide or sodium, potassium or ammonium perborates, percarbonates or perphosphates, such as sodium perborate, potassium perborate, sodium percarbonate, potassium percarbonate, ammonium perphosphate, sodium perphosphate, etc.

With respect to the production of lighter, appealing looking hair dye compositions, the ascorbic acid and salts thereof is at least equal in effect to the commonly used reducing agents such as thioglycolic acid or sulfites, while with respect to the obtaining of a deep coloring effect and coloring development, the ascorbic acid and salts thereof of the present invention gives far superior results.

With coloring agents to which an oxidation agent is added to cause the dyeing effect, for example p-phenylenediamine or p-toluylenediamine, with or without tinting dyestuffs from the class of aromatic amines or phenols, the lightness of color with addition of ascorbic acid or its salts in the produced dyestuff composition is comparable with the lightness of color obtained by the use of thioglycolic acid additives to the dyestuff compositions, both of these additions giving a markedly lighter color than with the addition of sulfate to the composition. After mixing with oxidation agents, however, in the case of thioglycolic acid or sulfite additives the resulting dyestuff composition very rapidly darkens, so that by the time the same can be applied to the hair it has a dark color, where-

as with dyestuff compositions according to the present invention containing the addition of ascorbic acid or its salts the lightness of color is maintained for a longer time and the composition becomes dark much slower.

5 This surprising effect, which will be further discussed below, is of importance for two reasons. In the first place it is much easier for the beautician to work with such composition, and secondly, this is an aesthetic advantage because the person, for example a woman having her hair dyed does not like a dark solution to be put onto the hair, particularly where the hair is to be dyed blond, for example.

The surprising effect of the ascorbic acid and its salts of first preventing premature oxidation by atmospheric oxygen, and in spite of the retarding of the dark color in the dyestuff mass after the addition of the oxidation agent then actually resulting in a more intensive dyeing is apparently due to the fact that the ascorbic acid at first has an antioxidantizing effect, and then, due to the formation of dehydroascorbic acid, has a prooxidizing effect.

Immediately after the addition of the oxidizing agent the antioxidantizing effect of the ascorbic acid occurs, while the prooxidizing action is being built up in the mass as the dehydroascorbic acid is being formed.

25 Only ascorbic acid and its salts gives this double action in the hair dye compositions to which the same is added, this action not being achieved with the use of any of the reducing agents used in such compositions prior to the present invention. The antioxidative action of ascorbic acid, thioglycolic acid and sodium sulfite all prevent premature oxidation of the dyestuff, but only with ascorbic acid is there formed a compound (dehydroascorbic acid) which has a prooxidizing effect. In the case of thioglycolic acid and sodium sulfate, the compounds resulting in the mass by the use of thioglycolic acid and sodium sulfite, respectively, as antioxidantizing agents, the same are inactive.

The principal distinct behavior characteristics of ascorbic acid in the presence of hydrogen peroxide in hair 40 dyestuff compositions based on the use of p-toluylenediamine as dyestuff is shown in FIGS. 1-3 of the drawings. The curves give the increase in darkness of the dyestuff after the addition of hydrogen peroxide, measured in percentual absorption with a photoelectric colorimeter (Dr. B. Lange, Model V) with an inserted green filter, in a 45 100 cc. flask, during a time period of 30 minutes. The dyestuff, which directly before the measurement is mixed with an equal volume of 6% hydrogen peroxide, contained in different tests normal reduction equivalent amounts of ascorbic acid, thioglycolic acid or sodium sulfite. The dyestuff agents had the compositions set forth in the following examples, in which Examples 1-4 correspond to FIGS. 1-4, respectively.

Example 1

55	p-Toluylenediamine-sulfate (0.01 mol) -----g--	2.2
	Sodium hydroxide (0.02 mol) -----g--	0.8
	Ethylenediaminetetraacetic acid, disodium salt -----g--	0.1
	Aqueous ammonia solution, 25% -----cc--	5.0
	Reducing agent and water, q.s. -----cc--	100

Reducing agent:

60	(a) Ascorbic acid (0.001 mol) -----g--	0.176
	Sodium hydroxide (0.002 mol) -----g--	0.08
	(b) Thioglycolic acid, 80% (0.002 mol) -----g--	0.23
	Sodium hydroxide (0.004 mol) -----g--	0.16
65	(c) Sodium sulfite (0.001 mol) -----g--	0.126
	(d) Without reducing agent	

Example 2

	p-Toluylenediamine-sulfate (0.01 mol) -----g--	2.2
	m-Phenylenediamine-dihydrochloride (0.01 mol) -----g--	1.8
70	Sodium hydroxide (0.04 mol) -----g--	1.6
	Ethylenediaminetetraacetic acid, disodium salt -----g--	0.1
	Aqueous ammonia solution, 25% -----cc--	5.0
	Reducing agent and water, q.s. -----cc--	100.0
75	Reducing agents as in Example 1	

Example 3

p-Toluylenediamine-sulfate (0.005 mol)	g--	1.1
m-Phenylenediamine-dihydrochloride (0.005 mol)	g--	0.9
Sodium hydroxide (0.02 mol)	g--	0.8
Ethylenediaminetetraacetic acid, disodium salt	g--	0.1
Aqueous ammonia solution, 25%	cc--	5.0
Reducing agent and water, q.s.	cc--	100.0
Reducing agents as in Example 1.		

Prior to the addition of the hydrogen peroxide the various dyestuff solutions have the following absorption values:

- 1.—(a) 18%; (b) 20%; (c) 18%; (d) 46%.
 2.—(a) 21%; (b) 20%; (c) 72%; (d) 83%.
 3.—(a) 10%; (b) 15%; (c) 21%; (d) 33%.

In the case of dyestuff agents where the dyeing is achieved by air oxidation, for example compositions containing 2,4-diaminophenol as oxidation dyestuff, it is not possible to use the known reducing agents because during the coloring process the oxidation by the atmospheric oxygen is so interfered with that only a relatively mild coloring can be achieved. If, on the other hand, no reducing agent is added to such dyestuff composition which is to be dyed by air oxidation alone, there is obtained even when using the fastest possible production methods and filling methods because of premature oxidation a deep coloring of the dyestuff and the dyestuff composition has only a relatively slight dyeing power. Consequently there has been suggested for such dyeing compositions the use of particular conditions, such as production and filling under nitrogen atmosphere in order to prevent premature oxidation.

However, if ascorbic acid is added to such dyeing agents, it is possible to carry out the production and filling in open apparatus. With respect to the dyeing result with such dyeing agents, which by air are easily oxidized, the poor oxidative action of the dehydroascorbic acid formed during the prevention of dyeing is of particular value, because with the addition of the ascorbic acid according to the present invention there is obtained a dyeing which is considerably deeper than could be previously obtained with such dyeing agents, even when the same were produced and filled under a nitrogen atmosphere.

With respect to the obtainable depth of coloring, the following sequence can be drawn up:

Maximum depth of color	Ascorbic acid addition.
Lesser depth of color	Production under nitrogen.
Still lesser depth of color	Production in air and rapid use.
Unsatisfactory depth of color	Addition of thioglycolic acid or sodium sulfite.

This outstanding activity of ascorbic acid (and its salts) is apparently due to its particularly rapid oxidizability. Because of this rapid oxidation what results is that during the time period for the dyeing of about 30 minutes the reduction agent is practically completely used up and the oxidation of the dyestuff is no longer interfered with. The formed dehydroascorbic acid can then, in addition, act completely with respect to its pro-oxidative action. With prior known reducing agents, on the other hand, the speed of oxidation by air is considerably slower so that a reducing action is always occurring during the time period for the dyeing action, and as a result the oxidation of the dyestuff is interfered with. Furthermore, no pro-oxidative action of the oxidation product is obtained with any of the known reducing agents.

Example 4

The decisive difference in the speed of oxidation is shown in FIG. 4.

Aqueous reduction equivalent amounts of ascorbic acid, thioglycolic acid and sodium sulfite are shaken in an oxygen atmosphere of accurately determined volume and the amount of oxygen used up in relationship to the time is measured. The solutions have the following compositions:

(a) Ascorbic acid (0.001 mol)	g--	0.176
Sodium hydroxide (0.002 mol)	g--	0.08
Water, q.s.	cc--	100.0
(b) Thioglycolic acid, 80% (0.002 mol)	g--	0.23
Sodium hydroxide (0.004 mol)	g--	0.16
Water, q.s.	cc--	100.0
(c) Sodium sulfite (0.001 mol)	g--	0.126
Sodium hydroxide (0.001 mol)	g--	0.04
Water, q.s.	cc--	100.0

From FIG. 4 it is clear that the ascorbic acid is already oxidized after a few minutes, while the oxidation of thioglycolic acid and sodium sulfite is not completely even after hours. By selection of suitable ascorbic acid concentration it is possible to adjust at will the time within 30 minutes that the ascorbic acid is completely used up. The ascorbic acid concentration is preferably so chosen that the coloring mass is in contact with the hair for 5 to 10 minutes before the ascorbic acid is used up.

The superior activity of ascorbic acid in hair dyestuff compositions is apparent from the following comparison dyeings:

Example 5

Light blond human hair is wetted with the dyeing agent, permitted to stand for 30 minutes in the air, and then rinsed and dried. The dyeing agents have the following compositions:

(a) 2,4 - diaminophenol - dihydrochloride (0.01 mol)	g--	1.96
Sodium hydroxide (0.02 mol)	g--	0.8
Ethylenediaminetetraacetic acid, disodium salt	g--	0.1
Aqueous ammonia solution, 25%	cc--	5.0
Water, q.s.	cc--	100.0
Production and filling under nitrogen atmosphere.		
(b) As in (a), however production and filling under an atmosphere, rapid working.		
(c) As in (b), however, with the addition of:		
Ascorbic acid (0.01 mol)	g--	1.76
Sodium hydroxide (0.02 mol)	g--	0.8
(d) As in (b), however with the addition of:		
Thioglycolic acid, 80% (0.02 mol)	g--	2.3
Sodium hydroxide (0.04 mol)	g--	1.6
(e) As in (b), however with the addition of:		
Sodium sulfite (0.01 mol)	g--	1.26

The color of these dyeing agents as well as the obtained depth of color of the hair dyed therewith is set forth in the following table:

Dyeing agent according to Example	Color of the dyestuff composition	Color of the dyed hair
5a	Weak yellowish	Medium blond.
5b	Deep blue violet	Light blond.
5c	Weak yellowish	Dark blond.
5d	do	Light-light blond.
5e	Dark brown	Do.

The following examples further illustrate hair dyestuff compositions according to the present invention:

Example 6

Gray human hair is wetted with 50 cc. of a dyeing agent which shortly before use is mixed with 50 cc. of 6% hydrogen peroxide, after 30 minutes of working time is rinsed, and then dried.

The dyeing agent has the following composition:

Oleic acid	g.	35.0
Isopropyl alcohol	cc.	15.0
25% aqueous ammonia solution	cc.	18.0
Ascorbic acid	g.	0.3
p-Toluylenediamine-sulfate	g.	0.8
2,4-diaminoanisol-sulfate	g.	0.06
m-Aminophenol	g.	0.1
Resorcinol	g.	0.2
p-Aminophenol	g.	0.3

The dyeing agent has a weakly yellow color and it dyes the hair to a dark ash blond tone with good covering.

Example 7

20 g. of cetyl alcohol, 2 g. of sodium cetyl sulfate and 5 g. of wool wax are heated to melting and emulsified with 30 g. of water at 70° C. Into the still hot emulsion is introduced a hot solution of 1.1 g. of p-toluylenediamine-sulfate, 0.1 g. of 2,4-diaminoanisol-sulfate, 0.04 g. of m-aminophenol, 0.3 g. of resorcinol, 0.1 g. of sodium sulfate, 0.5 g. of ascorbic acid as well as 10 cc. of 25% aqueous ammonia solution in 33 cc. of water, and the mixture is stirred until cooled.

For dyeing, 25 g. of the obtained ivory white colored cream is mixed with 25 cc. of 6% hydrogen peroxide. Gray human hair is covered therewith and after 30 minutes of action time is rinsed and dried. The hair is thereby dyed to a medium brown color.

Example 8

5.0 g. of sodium lauryl sulfate, 8.0 cc. of 25% aqueous ammonia solution, 0.2 g. of disodium salt of ethylenediamine tetraacetic acid and 1.0 g. of ascorbic acid are dissolved in 60 cc. of water, and then mixed with a solution of 2.0 g. of 2,4-diaminophenol-dihydrochloride in 20 cc. of water and diluted with water to a volume of 100 cc. This slightly yellowish solution is used to wet gray human hair, and the hair after 30 minutes of action thereon is rinsed and dried. The hair is thus thoroughly dyed to a hazelnut blond color.

Without further analysis, the foregoing will so fully reveal the gist of the present invention that others can by applying current knowledge readily adapt it for various applications without omitting features that from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A composition for dyeing human hair, comprising an oxidation hair dyestuff adapted upon oxidation to dye human hair; an oxidizing agent; and a compound selected from the group consisting of ascorbic acid and salts thereof.

2. A composition for dyeing human hair, comprising an alkaline carrier adapted for application to human hair; an oxidation hair dyestuff adapted upon oxidation to dye human hair and being in an amount of about 0.1-8% by weight; and a compound selected from the group consisting of ascorbic acid and inorganic salts and organic amine salts thereof in an amount of about 0.05 to 10% by weight.

3. A composition for dyeing human hair, comprising an alkaline carrier adapted for application to human hair; an oxidation hair dyestuff adapted upon oxidation to dye human hair and being in an amount of about 0.1-8% by weight; a compound selected from the group consisting of ascorbic acid and inorganic salts and organic amine salts thereof in an amount of about 0.05 to 10% by weight; and an oxidizing agent in an amount sufficient to oxidize said compound and said dye to thereby activate said dye and cause dyeing of human hair to which the composition is applied.

4. A composition for dyeing human hair, comprising an alkaline carrier adapted for application to human hair; an oxidation hair dyestuff adapted upon oxidation to dye human hair and being in an amount of about 0.1-8% by weight; a compound selected from the group consisting of ascorbic acid and inorganic salts and organic amine salts thereof in an amount of about 0.05 to 10% by weight; and an oxidizing agent selected from the group consisting of hydrogen peroxide, urea peroxide and sodium, potassium and ammonium perborates, percarbonates and perphosphates in an amount sufficient to oxidize said compound and said dye to thereby activate said dye and cause dyeing of human hair to which the composition is applied.

5. A composition for dyeing human hair, comprising an oxidation hair dyestuff adapted upon oxidation to dye human hair and being selected from the group consisting of o-phenylenediamine, p-phenylenediamine, 4-nitro-o-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-chlorotoluene-3,5-diamine, 4-methoxy-m-phenylenediamine, 4-methoxy-m-phenylenediamine-sulfate, 5-methoxy-p-phenylenediamine, 4-ethoxy-m-phenylenediamine, 4-ethoxy-m-phenylenediamine-sulfate, p-phenylenediamine-dihydrochloride, 2-chloro-p-phenylenediamine, 2-chloro-p-phenylenediamine-sulfate, 2-nitro-p-phenylenediamine, 3-(p-aminoanilino)-1,2-propanediol, N-phenyl-p-phenylenediamine, N-phenyl-p-phenylenediamine-hydrochloride, 4,4'-diaminodiphenylamine, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol, 1,5-naphthalenediol; and a compound selected from the group consisting of ascorbic acid and salts thereof.

6. A composition for dyeing human hair, comprising an alkaline carrier adapted for application to human hair; an oxidation hair dyestuff adapted upon oxidation to dye human hair and being selected from the group consisting of o-phenylenediamine, p-phenylenediamine, 4-nitro-o-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-chlorotoluene-3,5-diamine, 4-methoxy-m-phenylenediamine, 4-methoxy-m-phenylenediamine-sulfate, 5-methoxy-p-phenylenediamine, 4-ethoxy-m-phenylenediamine, 4-ethoxy-m-phenylenediamine-sulfate, p-phenylenediamine-dihydrochloride, 2-chloro-p-phenylenediamine, 2-chloro-p-phenylenediamine-sulfate, 2-nitro-p-phenylenediamine, 3-(p-aminoanilino)-1,2-propanediol, N-phenyl-p-phenylenediamine, N-phenyl-p-phenylenediamine-hydrochloride, 4,4'-diaminodiphenylamine, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol, 1,5-naphthalenediol and being in an amount sufficient to dye the hair to which the composition is applied; and a compound selected from the group consisting of ascorbic acid and inorganic salts and organic amine salts thereof in an amount of about 0.05 to 10% by weight.

7. A composition for dyeing human hair, comprising an alkaline carrier adapted for application to human hair; an oxidation hair dyestuff adapted upon oxidation to dye human hair and being selected from the group consisting of o-phenylenediamine, p-phenylenediamine, 4-nitro-o-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-

chlorotoluene - 3,5 - diamine, 4 - methoxy - m - phenylenediamine, 4-methoxy-m-phenylenediamine-sulfate, 5-methoxy-p-phenylenediamine, 4-ethoxy-m-phenylenediamine, 4-ethoxy-m-phenylenediamine-sulfate, p-phenylenediamine-dihydrochloride, 2-chloro-p-phenylenediamine, 2-chloro-p-phenylenediamine-sulfate, 2-nitro-p-phenylenediamine, 3-(p-aminoanilino)-1,2 propanediol, N-phenyl-p-phenylenediamine, N-phenyl-p-phenylenediamine-hydrochloride, 4,4'-diaminodiphenylamine, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol, 1,5-naphthalenediol and being in an amount of about 0.1-8% by weight; a compound selected from the group consisting of ascorbic acid and inorganic salts and organic amine salts thereof in an amount of about 0.05 to 10% by weight; and an oxidizing agent in an amount sufficient to oxidize said compound and said dye to thereby activate said dye and cause dyeing of human hair to which the composition is applied.

8. A composition for dyeing human hair, comprising an alkaline carrier adapted for application to human hair; an oxidation hair dyestuff adapted upon oxidation to dye human hair and being present in an amount of about 0.1-8% by weight, said oxidation hair dyestuff being selected from the group consisting of o-phenylenediamine, p-phenylenediamine, 4-nitro-o-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-chlorotoluene-3,5-diamine, 4-methoxy-m-phenylenediamine, 4-methoxy-p-phenylenediamine, 4-ethoxy-m-phenylenediamine-sulfate, p-phenylenediamine-dihydrochloride, 2-chloro-p-phenylenediamine, 2-chloro-p-phenylenediamine-sulfate, 2-nitro-p-phenylenediamine, 3-(p-aminoanilino)-1,2-propanediol, N-phenyl-p-phenylenediamine, N-phenyl-p-phenylenediamine-hydrochloride, 4,4'-diaminodiphenylamine, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol and 1,5-naphthalenediol; a compound selected from the group consisting of ascorbic acid and inorganic salts and organic amine salts thereof in an amount of about 0.05 to 10% by weight; and an oxidizing agent selected from the group consisting of hydrogen peroxide, urea peroxide and sodium, potassium and ammonium perborates, percarbonates and perphosphates in an amount sufficient to oxidize said compound and said dye to thereby activate said dye and cause dyeing of human hair to which the composition is applied.

9. The method of dyeing human hair, which comprises applying to human hair to be dyed in an alkaline medium a compound selected from the group consisting of ascorbic acid and inorganic salts and organic amine salts thereof, and an oxidation hair dyestuff adapted upon oxidation by atmospheric oxygen to dye the hair.

10. The method of dyeing human hair, which comprises applying to human hair to be dyed in an alkaline medium a compound selected from the group consisting of ascorbic acid and inorganic salts and organic amine salts thereof, an oxidation hair dyestuff adapted to be oxidized by an oxidizing agent and upon oxidation to dye the hair, and an oxidizing agent for said oxidation hair dyestuff.

11. The method of dyeing human hair, which comprises applying to human hair to be dyed an alkaline carrier containing about 0.05% to 10% by weight of a compound selected from the group consisting of ascorbic acid and inorganic salts and organic amine salts thereof, and also containing an oxidation hair dyestuff adapted upon oxidation by atmospheric oxygen to dye the hair.

12. The method of dyeing human hair, which comprises applying to human hair to be dyed an alkaline carrier containing about 0.05% to 10% by weight of a compound selected from the group consisting of ascorbic acid and inorganic salts and organic amine salts thereof, and also containing about 0.1-8% by weight of an oxidation hair dyestuff adapted upon oxidation by atmospheric oxygen to dye the hair.

13. The method of dyeing human hair, which comprises applying to human hair to be dyed an alkaline carrier containing about 0.05% to 10% by weight of a compound selected from the group consisting of ascorbic acid and inorganic salts and organic amine salts thereof, and also containing an oxidation hair dyestuff adapted to be oxidized by an oxidizing agent and upon oxidation to dye the hair, and oxidizing agent for said oxidation hair dyestuff.

14. The method of dyeing human hair, which comprises applying to human hair to be dyed an alkaline carrier containing about 0.05% to 10% by weight of a compound selected from the group consisting of ascorbic acid and inorganic salts and organic amine salts thereof, and also containing an oxidation hair dyestuff adapted to be oxidized by an oxidizing agent and upon oxidation to dye the hair, and an oxidizing agent for said oxidation hair dyestuff selected from the group consisting of hydrogen peroxide, urea peroxide and sodium, potassium and ammonium perborates, percarbonates and perphosphates.

15. The method of dyeing human hair, which comprises applying to human hair to be dyed in an alkaline medium a compound selected from the group consisting of ascorbic acid and inorganic salts and organic amine salts thereof, and an oxidation hair dyestuff adapted upon oxidation by atmospheric oxygen to dye the hair and being selected from the group consisting of o-phenylenediamine, p-phenylenediamine, 4-nitro-o-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-chlorotoluene-3,5-diamine, 4-methoxy-m-phenylenediamine, 4-methoxy-p-phenylenediamine, 4-ethoxy-m-phenylenediamine, 4-ethoxy-m-phenylenediamine-sulfate, p-phenylenediamine-dihydrochloride, 2-chloro-p-phenylenediamine, 2-nitro-p-phenylenediamine, 3-(p-aminoanilino)-1,2-propanediol, N-phenyl-p-phenylenediamine, N-phenyl-p-phenylenediamine-hydrochloride, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol, 1,5-naphthalenediol.

16. The method of dyeing human hair, which comprises applying to human hair to be dyed an alkaline carrier containing about 0.05% to 10% by weight of a compound selected from the group consisting of ascorbic acid and inorganic salts and organic amine salts thereof, and also containing an oxidation hair dyestuff adapted to be oxidized by an oxidizing agent and upon oxidation to dye the hair and being selected from the group consisting of o-phenylenediamine, p-phenylenediamine, 4-nitro-o-phenylenediamine-dihydrochloride, m-phenylenediamine, 4-chloro-m-phenylenediamine, 4-nitro-m-phenylenediamine, toluene-2,4-diamine, salts of toluene-2,4-diamine, toluene-2,5-diamine, 5-nitrotoluene-2,4-diamine, toluene-2,5-diamine-sulfate, 2-chlorotoluene-3,5-diamine, 4-methoxy-m-phenylenediamine, 4-methoxy-p-phenylenediamine, 4-ethoxy-m-phenylenediamine, 4-ethoxy-m-phenylenediamine-sulfate, p-phenylenediamine-dihydrochloride, 2-chloro-p-phenylenediamine, 2-chloro-p-phenylenediamine-sulfate, 2-nitro-p-phenylenediamine, 3-(p-aminoanilino)-1,2-propanediol, N-phenyl-p-phenylenediamine, N-phenyl-p-phenylenediamine-hydrochloride, 4,4'-diaminodiphenylamine-dihydrochloride, resorcinol, 4-chlororesorcinol, pyrogallol, p-aminophenol, 2-amino-4-nitrophenol, picramic acid, m-aminophenol, p-aminophenol-hydrochloride, 1-naphthol, 1,5-naphthalenediol.

p-phenylenediamine, 3-(p-aminoanilino)-1,2-propanediol, N-phenyl-p-phenylenediamine, N - phenyl-p-phenylenediamine-hydrochloride, 4,4'-diaminodiphenylamine, 4,4'-diaminodiphenylamine-dihydrochloride, resorcinol, 4-chloro-resorcinol, pyrogallol, p-aminophenol, 2-amino-4-nitrophenol, picramic acid, m-aminophenol, p-aminophenol-hydrochloride, 1-naphthol, 1,5 - naphthalenediol, and an oxidizing agent for said oxidation hair dyestuff selected from the group consisting of hydrogen peroxide, urea peroxide and sodium, potassium and ammonium perborates, percarbonates and perphosphates.

17. A composition for dyeing human hair comprising p-phenylenediamine and a compound selected from the group consisting of ascorbic acid and inorganic salts and organic amine salts thereof.

18. A composition for dyeing human hair comprising p-toluenediamine and a compound selected from the group consisting of ascorbic acid and inorganic salts and organic amine salts thereof.

19. A composition for dyeing human hair comprising 5-methoxy-p-phenylenediamine and a compound selected from the group consisting of ascorbic acid and inorganic salts and organic amine salts thereof.

20. The method of dyeing human hair, which comprises applying to human hair to be dyed in an alkaline medium an effective amount of a compound selected from the group consisting of ascorbic acid and inorganic salts and organic amine salts thereof, and an effective amount of an oxidation hair dyestuff selected from the group consisting of p-phenylenediamine, p-toluenediamine and 5-methoxy-p-phenylenediamine.

21. A composition for dyeing human hair, comprising in an alkaline medium an oxidation hair dyestuff adapted upon oxidation to dye human hair; and the sodium salt of ascorbic acid.

22. A composition for dyeing human hair, comprising in an alkaline medium an oxidation hair dyestuff adapted upon oxidation to dye human hair; and the potassium salt of ascorbic acid.

23. A composition for dyeing human hair, comprising in an alkaline medium an oxidation hair dyestuff adapted upon oxidation to dye human hair; and the ammonium salt of ascorbic acid.

24. A composition for dyeing human hair, comprising in an alkaline medium an oxidation hair dyestuff adapted upon oxidation to dye human hair; and an organic amine salt of ascorbic acid.

25. A method for dyeing living human hair comprising applying to the human hair an oxidation hair dyestuff and a compound selected from the group consisting of ascorbic acid and salts thereof.

26. A composition for dyeing human hair comprising an oxidation hair dyestuff; and a compound selected from the group consisting of ascorbic acid and salts thereof.

27. A composition as defined in claim 26, wherein said salt is selected from the group consisting of inorganic salts and organic amine salts of ascorbic acid.

28. A composition as defined in claim 26, wherein said oxidation hair dyestuff and said compound are incorporated in an alkaline medium.

29. A composition as defined in claim 28, wherein said salt is selected from the group consisting of inorganic salts and organic amine salts of ascorbic acid.

30. A method as defined in claim 25, wherein said compound and said oxidation hair dyestuff are applied in an alkaline medium.

31. A method as defined in claim 25, wherein said salt is selected from the group consisting of inorganic salts and organic amine salts of ascorbic acid.
